DESIGN FOR A COMBINED HEATING AND
COOKING STOVE.

Lee S. Chadwick, Shaker Heights, and Marc Resek
and Charles J. Kessler, Cleveland Heights,
Ohio, assignors to Perfection Stove Company,
Cleveland, Ohio, a corporation of Ohio

Application June 15, 1934, Serial No. 52,194

Term of patent 7 years

To all whom it may concern:

Be it known that we, LEE S. CHADWICK, MARC RESEK, and CHARLES J. KESSLER, citizens of the United States, residing at Shaker Heights Village, Cleveland Heights, and Cleveland Heights, respectively, in the county of Cuyahoga and State of Ohio, have invented a new, original, and ornamental Design for Combined Heating and Cooking Stoves, of which the following is a specification, reference being had to the accompanying drawings forming part hereof, wherein Figs. 1 and 2 are perspective views of a combined heat-

ing and cooking stove exhibiting our new design, the former view showing it closed for heating purposes and the latter view showing it open for cooking purposes. The two ends of the stove are the same.

We claim:

The ornamental design for a combined heating and cooking stove as shown and described.

LEE S. CHADWICK.
